UNITED STATES PATENT OFFICE.

ROBERT THOMPSON, OF ILLION, NEW YORK.

STARTING ATTACHMENT FOR EDISON PHONOGRAHS.

Application filed May 4, 1925. Serial No. 27,886.

My invention relates to a new and useful device for properly positioning the stylus or diamond point of an Edison phonograph, over the outer end of the sound groove, so that lowering of the tone-arm-and-horn-unit will properly engage the stylus with the beginning of the record.

It is one object of the invention to provide for obtaining the desired result in an exceptionally simple and inexpensive manner, and another aim is to provide an attachment for an ordinary Edison phonograph, which may be easily applied and adjusted to limit the swinging of the above-named tone-arm-and-horn-unit, toward the center of the record table, to a position at which the stylus is directly over the outer end of the sound groove, whereupon lowering of said unit will position the stylus in the groove.

United States Patents 1,184,333 of May 23, 1916, and 1,211,573 of January 9, 1917, show the general type of Edison phonograph with which my invention is usable.

With the foregoing in view, the invention resides in the novel subject matter hereinafter described and claimed, the description being supplemented by the accompanying drawing.

Figure 1 is a perspective view of an Edison phonograph equipped with the invention, the cover being swung upwardly and the front panel being removed.

Figure 2 is a detail horizontal sectional view showing the invention in top plan.

Figure 3 is an enlarged vertical sectional view on line 3—3 of Fig. 2.

Figure 4 is an enlarged detail horizontal section on line 4—4 of Fig. 3.

In the drawing above briefly described, U designates the well known tone-arm-and-horn-unit of an Edison machine, provided with the usual diamond point reproducer R for co-action with a record R' on the rotary table T. The unit U is mounted in the well known manner on a vertical shaft S having an operating handle H at its upper end, by means of which the unit may be raised and lowered, the shaft also acting as a pivot to allow said unit to swing horizontally. In the form of my invention herein disclosed, it co-acts with the front end of the horn of the unit U and is mounted on the bottom B of the compartment C in which all operating parts are located. The construction shown is here-

inafter rather specifically described, with the understanding however that within the scope of the invention as claimed, numerous modifications may be made.

The numeral 1 designates a substantially horizontal arm which is pivoted at 2 to the upper end of a post 3, this post being secured upon the bottom B. The outer end of this arm 1 is provided with a stop 4 which preferably carries a pad 5. The parts are so positioned that when the unit U is raised and the stylus of the reproducer R is clear of the record, the stop 4 is in the path on which the horn must travel when the unit U is horizontally swung to position the reproducer R over the outer edge of the record, and by the time swinging of said unit has taken place to the necessary extent to dispose the stylus directly over the outer end of the sound groove, the horn abuts the stop and thus can move no further at that particular time. Thus, when the handle H is operated to lower the unit U, the stylus necessarily engages the outer end of the sound groove. This downward movement of the unit U, disposes the horn below the stop 4, so that said unit may swing in the direction of the arrow in Fig. 2 to effect playing of the record. When the playing operation is over and the handle H is again depressed to elevate the unit U, this unit lifts the arm 1 about its pivot 2 and when said unit is returned to its idle position at the right-hand side of the cabinet C, the stop 4 drops from the horn and stands in readiness to again function.

In the preferred form of construction, the post 3 is stamped from a single piece of sheet metal, into channel-shape, and this post is provided with a horizontal base 6 having a slot 7 to receive an attaching screw 8, driven into the cabinet bottom B, the slot permitting the necessary adjustment of the device when it is initially installed.

The arm 1 is preferably formed also of a single piece of sheet metal and the stop 4 is formed by downwardly bending the outer end of this arm. To reinforce the arm, it is provided with vertical longitudinal flanges 9 whose inner ends are pivoted to the post 3, and to limit the downward swinging of said arm, its inner end is bent downwardly to provide a stop 10 which abuts the post 3 as shown clearly in Fig. 3.

In order to attach the pad 5 to the stop

4, the latter is preferably formed with two vertical slots 11 through which the ends of the pad are passed, said pad being preferably formed of leather, although this is not 5 essential. To hold the ends of the pad in the slots 11, the metal at the outer sides of these slots may well be bent inwardly to any required extent.

It will be seen from the foregoing that the 10 invention is extremely simple and inexpensive, yet that it is efficient, reliable, and may be easily installed and adjusted.

Excellent results have been obtained from the exact details disclosed and they are 15 therefore preferably followed. However, as above stated, modifications may of course be made within the scope of the invention as claimed.

I claim:

- 20 1. In combination with a phonograph having a record table and a tone-arm-and-horn-unit, the latter being mounted for vertical movement and for horizontal swinging; a stop adapted to abut a portion of said unit 25 when the latter is manually swung inwardly sufficiently to dispose the usual stylus at starting position with respect to a record on the table, and supporting means for said stop preventing descent of the latter when 30 the above-named unit is lowered to engage the stylus with the record, the aforesaid portion of said unit being movable under said stop throughout the record playing operation, said stop being adapted to be immediately 35 lifted by said unit when the latter is lifted and sustained thereby while said unit is being swung to inoperative position, said stop being then adapted to drop to operative position, in readiness for further use.
- 40 2. In combination with a graphophone having a record table and a tone-arm-and-horn unit, the latter being mounted for vertical movement and for horizontal swinging; a stop adapted to abut the outer end of the 45 horn of said unit when the latter is manually swung inwardly to dispose the usual stylus at starting position with respect to a record on the table, and supporting means for the stop preventing descent of the latter when the above-named unit is lowered to engage the stylus with the record, said 50 horn being movable under said stop throughout the record playing operation and being effective to lift said stop and sustain it when said unit is lifted and swung to inoperative position, said stop being then adapted to drop to operative position, in readiness for further use.

3. The combination defined in claim 1, in which said stop is formed by the free end of a pivotally mounted vertically swingable arm, said arm having a stop for limiting its downward movement, but being free to swing upwardly.

4. A device of the class described comprising a support adapted to be mounted in outwardly spaced relation with the horn of a tone-arm-and-horn-unit of a graphophone, an arm pivoted on a horizontal axis to said support, the free end of said arm being adapted to abut the horn when the tone-arm-and-horn-unit is positioned to dispose its stylus over the outer end of a record groove, and means for limiting the downward swinging of said arm.

5. A device of the class described comprising a support adapted to be mounted in outwardly spaced relation with the horn of a tone-arm-and-horn-unit of a graphophone, an arm pivoted on a horizontal axis to said support, the free end of said arm being adapted to abut the horn when the tone-arm-and-horn-unit is positioned to dispose its stylus over the outer end of a record groove, said arm having a stop adapted to strike said support and limit the downward swinging of said arm.

6. A structure as specified in claim 4; said support comprising a post having a base adapted to be secured upon the bottom of a phonograph cabinet.

7. A device of the class described comprising a vertical post having a horizontal base formed with a longitudinal slot, said slot being adapted to receive a screw for securing the base to the bottom of a graphophone cabinet in outwardly spaced relation with the horn of a tone-arm-and-horn-unit, a substantially horizontal arm pivoted to the upper end of said post on a transverse horizontal axis, the inner end of said arm having a downwardly extending stop to abut the post and limit the descent of the arm, the outer end of said arm having a stop to abut the above-named horn.

8. In a graphophone stylus-positioning device, a metal stop having a pair of spaced parallel slots, a pad at one side of said stop having its ends passed through and held in said slots, and means for mounting said stop with the pad disposed to abut a carrying part for the stylus.

In testimony whereof I have hereunto affixed my signature.

ROBERT THOMPSON.
